UNITED STATES PATENT OFFICE.

THEOPHILE ELPHEGE PONSON, OF PARIS, FRANCE.

SPARKING PLUG.

1,250,009.

Specification of Letters Patent. Patented Dec. 11, 1917.

Application filed June 4, 1917. Serial No. 172,695.

To all whom it may concern:

Be it known that I, THEOPHILE ELPHEGE PONSON, a citizen of the Republic of France, and resident of Paris, in the Republic of France, have invented new and useful Improvements in Sparking Plugs, of which the following is a specification.

The present invention has for its object a 10 sparking plug which is of very simple construction, does not include any packing of asbestos or other material, and is constructed in such a manner as to permit not only good insulation of the central electrode but also cooling of the upper part of the plug, and 15 more especially of this central electrode, by establishing an air current through the plug upwardly and about the central electrode.

The improved sparking plug is characterized essentially by a central electrode insulated from the metal body at its lower part 20 by an insulator sleeve in the form of a truncated cone fitting into the tubular part of the body which is of corresponding form internally, and at its upper part by a bell or cap of insulating material.

Apertures are formed in the body and at the upper part of the cap in a manner such as to enable air to circulate upwardly in the 30 interior of the cap and cool the central electrode. The central electrode is also provided with a head abutting against the insulating sleeve and protecting the same from the hot flames caused by the ignition, thereby increasing the life of the plug.

35 The invention is shown by way of example in the accompanying drawing, wherein:

Figure 1 shows an elevation of my spark plug;

Fig. 2 is an under side view of the same; 40 and

Fig. 3 is a vertical section through the plug.

As shown, the sparking plug comprises a 45 metal body or socket *a* provided with a screw threaded tubular part *b* which enables the plug to be fixed on an internal explosion engine. The tubular part *b* is internally of the form of a truncated cone, of which the part of smaller diameter is arranged at the upper part of the member *b*. In the tubular part *b* there fits an insulator sleeve *c* surrounding a rod *d* of the central electrode. The insulator sleeve *c* has a lower conical part fitting into the seat of the same shape 50 formed by the tubular part *b*. It has also an upper cylindrical part projecting above

the socket. The insulator sleeve *c* is formed by washers of mica fitted on to the rod *d* which is already insulated by its fitting into a tube *c'* also of mica. The washers bear at 60 the lower part of the rod *d* on a metal disk which may form an integral part of the rod or be retained thereon by a mushroom-head *d'*. The mica washers are tightened up in a press on the rod and are held in position on the rod *d* by a washer *l* of ivorine, fibrine or similar material, and also by a nut 10 which is threaded on the rod and which is embedded in the above mentioned material.

65 A bell or cap *e* surmounts the body *a*. It bears at its upper part a nut *o* which is in threaded engagement with the rod *b* of the central electrode, and by means of which said cap is secured in place. The cap has a reduced end which fits into a recess *a'* formed 70 in the socket *a*. The rod receives also above the cap a washer *p* and a lock nut *p'*. By reason of the height of the cap *e* the upper exposed part of the rod *d* of the central electrode is a considerable distance from the 75 mass of metal formed by the body *a*, thereby preventing the production of external sparks when the end of the plug is subjected to high pressure in the interior of the cylinder.

80 As mentioned above, the lower part of this central electrode is formed by a metal disk *h* which has an inner inwardly tapering face, against which face abuts the adjacent end of the insulator sleeve *c*. This engagement of the end of the insulator sleeve 85 with the disk protects the end of the electrode from direct effect of the high temperature of combustion. The disk has its outer 90 face arranged on the same plane as the end of the tubular part *b* of the body forming the earthed electrode. The disk is provided over the whole of its periphery with a beveled or feather edge *h'* arranged inside the tubular part *b* in such a manner that this 95 disk has a sharp edge arranged at a short distance from the internal circumference of the tubular part *b* and forming therewith a gap. The lower end of the insulator sleeve *c* is provided over all of its periphery with a beveled surface *c'* arranged in the opposite direction to the bevel *h'*. These two bevels 100 form an annular chamber *q* wherein residue from the combustion of the explosive mixture may lodge. This annular chamber having a restricted inlet formed by the electrodes prevents the high temperature present in the cylinder from entering into said 105 110

chamber and affecting the end of the insulator which terminates therein.

In my improved sparking plug the internal air chamber formed in the body *a* is very deep and the holes *i* at the periphery of the body open at the base of this chamber. Moreover, the holes *j* formed in the cap *e* are arranged at the upper part of this cap. This arrangement causes an upward air current through the air chamber and about the upper part of the sleeve and the exposed portion of the central electrode located within the said chamber.

From the above description it will be seen that the plug is formed of few parts which can be easily and quickly taken apart as, for example, by removing the nut *p* and washer the central electrode can be withdrawn with its insulator sleeve from the part *b*, cleaned and quickly restored.

I claim:

1. In a spark plug, a metal body having an internal upwardly tapering recess, an insulator sleeve having a tapering portion engaging said tapering recess, said insulator sleeve having at the larger end of its tapering portion a portion tapering in the opposite direction, and a central electrode anchored in said sleeve to present a circular sparking head which contacts with the adjacent end of the sleeve and which head forms a circular gap with the wall of the upwardly tapering opening in the body, said circular sparking head tapering in the same direction as the opening but having a greater obliquity, whereby a chamber is formed by the tapers in the body, the circular head and the lower portion of the insulator sleeve.

2. In a spark plug, a metal body, a central electrode having a circular sparking head presenting an inwardly tapering face,

an insulator sleeve having a tapering end engaging the tapering face of the head, said sleeve engaging the body, and means maintaining the end of the sleeve and face of electrode in firm contact, said sleeve and circular head forming a peripheral concave groove which, with the body, forms an annular chamber having a gap.

3. In a spark plug, a metal body having a socket at its upper end, an insulator sleeve mounted in the lower part of the body projecting through the socket, a central electrode in the sleeve projecting above the same, and an insulator cap engaging the socket and the central electrode and secured by the latter, said insulator cap and socket forming an annular chamber about the sleeve, the top of the cap being spaced from the top of the sleeve whereby a portion of the central electrode is in the said chamber, said chamber having openings in the lower and upper parts of the same whereby an air current is created therethrough and whereby the part of the electrode within said chamber is subject to the direct effect of the cooling air current.

4. In a spark plug, a central electrode, an insulator over the lower part of the electrode, and means forming a chamber about the upper portion of the insulator and the upper part of the electrode and secured by the latter, said chamber having means for causing an upward air current therethrough whereby the upper part of the electrode not covered by the insulator is subject to the cooling effect of the air current.

THEOPHILE ELPHEGE PONSOT.
